UNITED STATES PATENT OFFICE.

IRVING H. SEGAL, OF DETROIT, MICHIGAN.

DESIGN FOR A FINGER RING.

Application filed January 16, 1928. Serial No. 24,897. Term of patent 7 years

To all whom it may concern:

Be it known that I, IRVING H. SEGAL, a citizen of the United States, residing at Detroit, in the county of Wayne and State of Michigan, have invented a new, original, and ornamental Design for Finger Rings, of which the following is a specification, reference being had to the accompanying drawing, forming a part thereof.

Fig. 1 is a side elevation of the article, showing my new design.

Fig. 2 is a plan view thereof.

Fig. 3 is an edge elevation thereof.

What I claim is:

The ornamental design for a finger ring, as shown.

IRVING H. SEGAL.
